UNITED STATES PATENT OFFICE.

HERBERT H. ALLEN, OF BROOKSVILLE, FLORIDA.

PLOW ATTACHMENT FOR REGULATING DEPTH OF FURROWS.

SPECIFICATION forming part of Letters Patent No. 633,940, dated September 26, 1899.

Application filed July 29, 1899. Serial No. 725,507. (No model.)

To all whom it may concern:

Be it known that I, HERBERT H. ALLEN, a citizen of the United States, residing at Brooksville, in the county of Hernando and State of Florida, have invented certain new and useful Improvements in Plow Attachments for Regulating the Depth of Cutting Furrows; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in attachments to plow-beams for the purpose of regulating the depth at which it is desired to have the plow cut the furrow; and it consists in the provision of means whereby the driver of the team to which the plow is attached can by means of a lever having connection with the pivoted clips at the end of the plow-beam raise or lower the same and by so doing throw the draft on the beam at the upper or lower portion thereof accordingly as it is desired to have the plow cut a deep or shallow furrow.

More specifically the invention consists in an attachment for plow-beams for regulating the depth at which it is desired to have the furrow cut and comprises swinging plates which are pivoted near the end of the plow-beam and carrying the clevis to which the team is connected, said swinging plates having transverse slots in which antifriction-rollers are mounted upon stub-shafts, levers being connected to the swinging ends of said plates, and connections between said levers and an operating-handle whereby the plates may be raised or lowered by means of the operating-handle carried by suitable clamping mechanism on the plow-beam.

To these ends and to such others as the invention may pertain the same consists, further, in the novel construction, arrangement, and adaptation of parts, as will be herein-after more fully described and then specifically defined in the appended claims.

My invention is clearly illustrated in the accompanying drawings, which, with the let-

ters of reference marked thereon, form part of this application, and in which drawings I have shown, in—

Figure 1, a side elevation of my invention as applied to the beam of a plow. Fig. 2 is a plan view of the same, and Fig. 3 is an enlarged horizontal section through a portion of the plow-beam.

Reference now being had to the details of the drawings by letter, A designates a plow-beam of any known shape, and pivoted near the free end of said beam are the plates B, mounted on the pivots B', and each of said plates has a transverse and slightly-curved slot C, and at the ends of each plate are a series of holes D, in which the clevis E is adapted to be held. Mounted on the pins F, extending laterally from the opposite faces of the beam, are the antifriction-rollers G, which are of such a diameter as to snugly fit the curved transverse slots in said plates and to ride against the edges of said slots as the plates are raised and lowered. Secured to the beam are two clamping members, one of which is composed of two plates H and H', which are held together and to the beam by means of the bolts J passing through the angles of said plates. One of said plates H has an upturned projecting portion h, carrying a stub-shaft K, on which are pivoted the two angle-levers M, the forward ends of these angle-levers each carrying pivotal pins K', to which are pivoted the bars N, the outer ends of which are apertured and pivoted to a pin Q, which passes through registering apertures in the two plates B. The rear clamping member, or the one attached nearest to the handles of the plow-beam, is composed of two plates R and R', which are held to the beam by means of bolts S in a similar manner as the plates H and H' are held to the beam. One of said plates, R', has a series of segment-teeth T upon its upper curved edge. Pivoted on the pin R², which is the pin carried at the lower end of the plates R and R', is a lever L, to which lever is pivoted, as at V, a lever W, the other end of which is pivoted to the upper angles of each of the levers M, as at W'. By this connection it will be noted that as the said lever L is swung upon its pivot the plates B will be raised or lowered, which will

cause the clevis also to be raised or lowered, and accordingly the plow will cut deeper or shallower, as may be desired.

In order to hold the attachment in an adjusted position, I provide a spring-actuated pawl P, the lower end of which is adapted to engage with the teeth on the segment portion of the plate R', while its upper end is connected to the hand-operated lever P'.

Having thus described my invention, what I claim to be new, and desire to secure by Letters Patent, is—

1. An attachment to plow-beams for regulating the depth at which it is desired to cut a furrow, consisting of two plates pivoted to the opposite faces of the plow-beam, transverse slots in said plates, antifriction-rollers carried by the beam and guided in said slots, clamping devices held to the beam, and levers carried by said clamping devices, and having connection with said plates, and a hand operating-lever, whereby the plates may be raised or lowered, as shown and described.

2. An attachment to plow-beams to regulate the depth at which it is desired to cut a furrow, consisting in combination with the beam, of the two pivoted plates carried thereby, transverse slots therein, antifriction-rollers carried by the beam and guided in said slots, the clamping devices secured to said beam, one of which clamping devices has a pivoted hand-lever, angle-levers pivoted to an extension on the second of said clamping members, links connecting the forward ends of said angle-levers, and the swinging plates and a connection between the angle-levers and the operating-levers, whereby said plates may be raised or lowered, and held in an adjusted position, as shown and described.

In testimony whereof I affix my signature in presence of two witnesses.

HERBERT H. ALLEN.
